UNITED STATES PATENT OFFICE.

LEWIS C. MALTBY, OF WASHINGTON, DISTRICT OF COLUMBIA, ASSIGNOR TO THE STONE STRAW COMPANY, OF WASHINGTON, DISTRICT OF COLUMBIA, A CORPORATION OF NEW JERSEY.

CUT-OFF MECHANISM FOR MACHINES FOR MAKING ARTIFICIAL STRAWS.

1,208,600.

Specification of Letters Patent.

Patented Dec. 12, 1916.

Application filed February 12, 1916. Serial No. 78,057.

To all whom it may concern:

Be it known that I, LEWIS C. MALTBY, a citizen of the United States, residing at Washington, in the District of Columbia, have invented certain new and useful Improvements in Cut-Off Mechanism for Machines for Making Artificial Straws, of which the following is a specification.

My invention relates to improved cut-off mechanism for machines for making artificial straws, and it consists in a periodically and positively rotated shaft which carries an eccentric which latter imparts an endwise and lateral movement to a rotary disk-cutter at predetermined intervals, the cutter and its shaft being carried by a rocking frame, which the eccentric causes to swing laterally as well as move longitudinally.

In the accompanying drawings: Figure 1 is a plan view of one end of the machine, showing the cut-off mechanism; Fig. 2 is a side elevation of the same; Fig. 3 is a section on the line 3—3 of Fig. 1; Fig. 4 is a section on line 4—4 of Fig. 1, both of the latter figures looking in the direction of the arrows; and Fig. 5 is a detail in perspective of the collars 20 and 21 and connected parts.

A, is the bed of the machine, which may be cast in any approved form and size, it being adapted to be mounted on suitable legs (not shown). Erected on the bed are brackets 1, 1, where they are held by bolts or other means 2, 2. There are two of these brackets. Arms 3, 3, extend laterally from the bed, and at their upper ends revolvably support the counter-shaft 4; and boxes 5, 5, secured on these arms support the driven-shaft 6. This driven-shaft 6 carries the eccentric 7 which is keyed thereon, and also it has a pinion 8 keyed on it. This pinion 8 has a predetermined number of teeth, for instance twelve, and is adapted with each periodical movement to make a complete revolution. This is accomplished by the teeth on the mutilated gear-wheel 9, which is keyed on countershaft 4, there being twelve of these teeth occupying a fourth of the peripheral surface of the mutilated gear, so that pinion 8 is given one complete rotation during a fourth of a revolution of wheel 9 and stands still during the remaining three-fourths of its revolution. The countershaft 4 is continuously rotated through

the large gear 10, the teeth of which mesh with the intermediate wheel 11, and the latter is driven by the pinion 12 on the drive-shaft 13.

Around the eccentric the usual eccentric strap 14 is placed, and this is connected to the bell crank lever 15 by means of the ball-joint 16, where it is held by the bolts 17, 17, extending through the ends of the strap, one on each side thereof. The long arm of the bell crank lever 15 is pivotally connected to a tail-piece 18 rigidly secured to or integral with the web 19 of the two collars 20 and 21. These collars 20 and 21 are secured to the sleeve 22, which insheathes the shaft 23, which carries the disk-cutter 24 and the rod 25 respectively; and as the sleeve 22 is slidably mounted in the collars 26, 26, carried by the upper end of the rocking frame 27, and the straw-tube 28 through the bar 29 is slidably mounted in the upper ends of the brackets 1, 1, and the collar 20 is connected with the bar 29 through guide-plate 30, sliding between the anti-friction rollers 31, 31, carried by the sleeve 32 secured on the bar 29, as clearly set forth in one of the accompanying concurrently pending applications, it will be seen that the rotation of the eccentric 7 swings the bell-crank lever 15 rapidly back and forth, and in so doing it reciprocates the saw-shaft 23, sleeve 22, straw tube 28, and bar 29, and simultaneously rocks the frame 27 in which the shaft 23 and sleeve 22 are carried, thus causing the parts to move with the straw, and the saw-disk to move across the path of the latter once during each single rotation of the mutilated gear 9. Shaft 23 is driven by a pulley 33 and a belt 34 passing around the latter to the main drive-shaft or some other source of power (not shown). Thus it will be seen as disk-cutter 24 is secured on one end of the shaft 23 at one end of the sleeve 22, and pulley 33 on the other end of shaft 23 at the opposite end of sleeve 22, that the endwise movement of the sleeve 22 through the bell-crank-lever 15, will cause the shaft 23 carrying the disk cutter 24 to likewise be moved endwise.

I claim:

1. The combination of a bed, a rocking frame mounted thereon, a sleeve connected with said frame, a shaft rotatable in the sleeve and carrying a disk-cutter, a straw-

tube slidably connected with the bed, and means extending from the sleeve and slidably connected with the straw-tube for moving the latter endwise with the endwise movement of the disk-cutter.

2. The combination of a bed, a rocking frame, a slidably-mounted straw-tube, and endwise movable means carried by the frame and extending laterally therefrom, 10 and slidably connected with the tube, whereby the frame is capable of moving laterally with respect to the straw-tube, and the endwise movable means carried thereby causes the straw-tube to move endwise with 15 the lateral movement of the frame.

3. The combination of a bed, a rocking frame, a slideable sleeve, a straw-tube, a bar connected with the straw-tube, common means for rocking the frame and sliding the sleeve, and means extending from the sleeve laterally and slidably connected with the bar for moving the latter endwise with the lateral movement of the frame and slideable sleeve.

25 4. The combination with a bed, a rocking frame mounted thereon, a sleeve slidably connected with said frame, a shaft rotatable in the sleeve and carrying a disk-cutter, a straw tube slidably connected with the bed, 30 means extending from the rocking frame and slidably connected with the straw tube for moving the latter endwise with the endwise movement of the disk-cutter, of an intermittently rotated shaft, an eccentric 35 thereon, and means extending from the eccentric to the rocking frame for reciprocating and swinging the latter laterally.

5. The combination with a bed, a rocking frame mounted thereon, a sleeve slidably 40 connected with said frame, a shaft rotatable in the sleeve and carrying a disk-cutter, a straw tube slidably connected with the bed, means extending from the rocking frame and slidably connected with the straw tube 45 for moving the latter endwise with the endwise movement of the disk-cutter, of a pair of shafts intermittently intergeared, an eccentric carried on one of said shafts, and means extending from the eccentric to the

rocking frame for reciprocating and swing- 50 ing the latter laterally.

6. The combination with a machine-bed or frame, a main drive-shaft, a countershaft and a driven-shaft carried thereby, the countershaft having a mutilated gear thereon, and the driven-shaft a pinion and an eccentric, of a rocking frame and sleeve carried thereby, a shaft rotatable in said sleeve and carrying a disk-cutter, a slideable straw tube, and means carried by the sleeve slidably connected with the straw tube for moving the latter endwise, an eccentric strap on the eccentric, and a bell crank lever operated by the eccentric strap and connected with the means carried by the sleeve for reciprocating the sleeve, the shaft therein, and the straw tube, and for simultaneously rocking the rocking frame and with it the tube and shaft therein.

7. The combination with a machine bed, 70 counter- and driven-shafts, one having a mutilated gear and the other a pinion which meshes with the mutilated gear, whereby the shaft having the pinion is given an intermittent rotary motion, an eccentric secured on the driven shaft, an eccentric shaft, and a bell-crank lever connected to the eccentric, of a rocking-frame, a sleeve carried thereby, a shaft rotatable in the sleeve and carrying a disk-cutter, a collar secured to 80 the sleeve and to which the bell-crank lever is pivotally connected, a guide-plate carried by the collar, brackets secured to the bed, a bar slidably connected with the brackets, a sleeve secured thereto and carrying anti-friction rollers between which the guide-plate on the collar slides, and a straw tube carried by the bar, whereby with the periodical rotation of the driven-shaft, the bell-crank lever is oscillated, and with it the 85 sleeve and shaft carrying the disk-cutter as well as the straw tube are reciprocated, and the saw-shaft and sleeve are oscillated, whereby the saw passes into and out of the path of the straw passing through the 90 straw-guide.

In testimony whereof I affix my signature.
LEWIS C. MALTBY.
